UNITED STATES PATENT OFFICE.

GEORGE P. KINGSBURY, OF BROOKLYN, NEW YORK, ASSIGNEE TO MERGENTHALER LINOTYPE COMPANY, A CORPORATION OF NEW YORK.

TYPOGRAPHICAL MACHINE.

1,121,021.

Specification of Letters Patent. Patented Dec. 15, 1914.

Application filed March 8, 1913. Serial No. 752,805.

To all whom it may concern:

Be it known that I, GEORGE P. KINGSBURY, a citizen of the United States, residing at Brooklyn, in the county of Kings and State of New York, have invented certain new and useful Improvements in Typographical Machines, of which the following is a specification, reference being had therein to the accompanying drawing.

- 10 This invention relates to machines in which a printing slug or bar is formed in a slotted mold and then delivered therefrom by an ejector blade which advances against the edge of the slug. In many of these machines the mold is variable or adjustable in length, in order to produce slugs for printing columns or pages of different widths; and in connection with such adjustable mold, is frequently employed a composite ejector, 15 having its parts so constructed and combined that its operative portion may be varied in width to correspond with changes in the length of the mold slot. As illustrated for instance in Letters Patent of the United States, No. 967,976, to John R. Rogers, the 20 ejector blade is composed of a series of parallel sections arranged edge to edge, and mechanism is provided whereby any desired number of these sections can be connected 25 with the actuating slide, while the others are left free therefrom. In the operation of such machines, it sometimes occurs, at the hands of an inexperienced or careless attendant, that an attempt is made to connect 30 or disconnect the sections at an improper time, and generally when the machine is in operation. This attempt sometimes results in injury to the parts, or in inconvenience and loss of time, which disadvantages it is 35 one of the objects of my invention to prevent. To this end, I construct the machine so that the ejector sections may be connected with and disconnected from the actuating devices only when the parts are in a pre- 40 determined position, and specifically when the machine is in its normal position of rest, and after the ejector is withdrawn from the mold, locking devices being provided to prevent such adjustment at any other time.
- 45 Another feature of my improvements is the provision of means whereby the ejector blades are normally held in the mold after the machine has reached its normal position, this being preferably effected by spring pressure; and thereby I avoid the liability

to their accidental displacement, which is frequently present in ordinary practice.

In the accompanying drawings, I have illustrated my invention in preferred form and by way of example, and as applied to 60 the style of machine already mentioned, but obviously many changes and variations may be made therein, and in its mode of application, and still be comprised within its spirit. Generally speaking, I desire it to be understood that I do not limit myself to any specific form or embodiment, except in so far as such limitations are specific in the claims.

Referring to the drawings: Figure 1 is a detached view of the ejector mechanism, 70 etc., with my improvements embodied therein, partly broken away, and illustrating the parts in the normal position of rest; Fig. 2 is a similar view, showing the parts immediately after their operation has begun; Fig. 75 3 is a sectional detail on an enlarged scale, taken substantially on the line 3—3 of Fig. 2; and Fig. 4 is a section on the line 4—4 of Fig. 2.

The mold A is mounted in the mold carrier or disk A', and the ejector is made up of a series of parallel blades or sections B connected to the ejector slide B', which is reciprocated through the link B² by the ejector lever C. The ejector lever is pivotally 80 mounted at C', and is provided with the cam shoe C² located in position to be actuated by the ejector cam D.

The parts so far described, and their mode of operation, are or may be substantially 90 like those disclosed in the said Rogers patent, or as embodied in the commercial linotype machine.

Connected to the ejector lever C is the arm C³, arranged to vibrate with it about the same pivotal point C', and connected to the arm C³ is the longitudinally-movable rod E carrying the block E', which is located in position to be engaged by the piece E² carried by the treadle lever F. The treadle F is normally held in its inoperative position by the spring F', and the rod E is provided with the surrounding spiral spring G, located between a collar E³ fast thereon and a collar E⁴ slidable thereon and bearing against the end of a lever arm H' pivotally mounted at H on the frame of the machine. The movement of the treadle F by the operator, through the connections described, 100 and as indicated by dotted lines in Fig. 1,

effects the withdrawal of the ejector from the mold to permit of its adjustment. These parts and their mode of operation, except in so far as hereinafter indicated, are or may be substantially like those disclosed in the application for Letters Patent of E. W. Pierson, Serial No. 701,043, filed June 1, 1912.

The ejector blades or sections B are directly engaged and actuated by the bar K, which receives its actuating movement from the ejector slide B', the bar K being slidably mounted at its lower end on the rod K' attached to the vertical slide K², which in turn may be raised or lowered by the hand lever K³, in order to connect the bar K with any desired number of blades or sections. The bar K is provided with the pin L, which normally travels forward and backward in one or another of the stationary grooves L', according to the number of sections B in operation, and whereby the bar K is held against vertical adjustment, until the pin L is shifted into the vertical groove M. These parts, and their mode of operation, are or may be substantially like those disclosed in the application for Letters Patent of David S. Kennedy, Serial No. 737,168, filed December 17, 1912.

As previously stated, it is the purpose of my invention to secure different and novel functions not present in the mechanisms already referred to; the first of these is the prevention of a change in the number of the ejector sections B, unless the machine be in its normal position of rest. It will be noted that the spring G on the rod E bears at one end against the arm H', which is formed with a second arm H² located beyond the pivotal point H, and which latter arm is normally in engagement with the cam surface J', arranged to rotate in unison with the ejector cam D. The cam surface J' is formed with a projecting cam piece J, so located that when the parts are in their normal position of rest, the cam piece contacts with the arm H² and thus holds the arm H' in its innermost position with relation to the spring G. The arm H' is bifurcated at its end so as to straddle the rod E and is provided with the transverse pin H¹⁰ which lies below and supports the rod. The rod E is formed in its lower side with the elongated notch E¹⁰, which is entered and engaged by the pin H¹⁰ in the circumstances subsequently to be described.

Fig. 1 illustrates the parts in their normal position of rest, at which time the ejector sections B project into the mold A, the cam piece J engages the arm H² so as to hold the arm H' firmly in its innermost position, and the cylindrical or unnotched portion of the rod E rests upon the pin H¹⁰. Under these conditions the ejector may be withdrawn from the mold and its width

then varied by including a greater or smaller number of the sections B. To this end, the treadle F is operated, and thereby the rod E and ejector lever C moved rearwardly, as indicated by dotted lines, the longitudinal movement of the rod E being unimpeded by the pin H¹⁰, and during this movement the spring G being compressed between the collar E² and the arm H¹. This operation withdraws the sections B from the mold A, and shifts the bar K to bring the pin L into the groove M, so as to permit the vertical movement of the pin in said groove. The parts are now free to be adjusted by the manipulation of the lever K³ so as to connect the bar K with any desired number of sections B, in the manner described in the said Kennedy application. After this operation, the pressure on the treadle F is relieved, and it is returned by the spring F¹ to normal position, and simultaneously the expansion of the compressed spring G returns the sections B into the mold A, in substantially the manner described in the said Pierson application. It will be noted, however, that in the present instance, and unlike the construction of the Pierson application, the abutment arm H¹ is held rigidly in position continuously while the machine occupies its normal position of rest, which result arises from the employment of operating means for the arm H², which are synchronously related to the ejector actuating mechanism. It therefore follows that all the time during this period the spring G has a solid abutment, and consequently it tends to resist any accidental displacement of the ejector from the mold. This feature is of importance in that it reduces the liability to the dropping out of the ejector blades, which sometimes occurs after a completion of the machine's cycle, and particularly when the mold is adjusted for short slugs.

The foregoing description demonstrates the feasibility of altering the width of the ejector blade when the machine is in its normal position of rest. It will now be shown that such alteration is impossible at other times.

Fig. 2 illustrates the parts immediately after the automatic actuation of the machine has been initiated. At this time the cam D has acted upon the shoe C² and moved the ejector lever C and connected parts rearwardly, thereby withdrawing the ejector from the mold. Simultaneously the cam projection J has passed from under the arm H², and the latter moves about its pivot H until it contacts with the cam surface J¹. The corresponding angular shifting of the connected arm H¹ moves the pin H¹⁰ into the notch E¹⁰ of the rod E, as also shown in Fig. 3, thereby locking the rod E against longitudinal movement, by the treadle F, 120

The previously-mentioned automatic rearward movement of the lever C and its connected parts is insufficient to bring the pin L into the vertical slot M, (see also Fig. 4), and as the rod E is now locked against movement, it is impossible to adjust the bar K vertically to connect it with a greater or less number of ejector sections B; and this condition persists until the parts have again resumed their normal position of rest, as illustrated in Fig. 1.

As previously stated, I have shown my invention only in preferred form and by way of example, but obviously many alterations and modifications in its construction and mode of application will suggest themselves to those skilled in the art without departure from its scope.

Having thus described my invention, its construction and mode of operation, what I claim and desire to secure by Letters Patent of the United States is, as follows:

1. In a typographical machine, the combination of a movable ejector variable in width, a single adjusting device for changing the width of said ejector, and means for preventing the operation of said device except when the machine is at rest.

2. In a typographical machine, the combination of ejector mechanism comprising a plurality of ejector sections, actuating means therefor, a single adjusting device for connecting the desired number of sections to the actuating means, and means for preventing the operation of said device except when the machine is at rest.

3. In a typographical machine, the combination of a mold, a movable ejector adapted to stand normally within the mold, devices for withdrawing the ejector from the mold at will, and means for preventing the operation of said devices except when the machine is at rest.

4. In a typographical machine, the combination of a movable ejector, devices operable at will for moving the ejector from its normal position of rest, locking means to prevent the movement of said devices during the operation of the machine, and automatic mechanism to release said locking means when the machine comes to rest.

5. In a typographical machine, the combination of a movable ejector variable in width, adjusting devices for controlling the width of said ejector, locking means to prevent the adjustment of said devices during the operation of the machine, and automatic means to release said locking means when the machine comes to rest.

6. In a typographical machine, the combination of a movable ejector variable in width, actuating mechanism therefor, adjusting devices for controlling the width of the ejector, means for preventing the adjustment of said devices, and automatic

means controlled by the said actuating mechanism to release said preventing means.

7. In a typographical machine, the combination of a movable ejector and adjusting devices for said ejector, the said devices comprising the longitudinally movable rod E for moving the ejector from its normal position of rest, and means for locking the rod against such movement.

8. In a typographical machine, the combination of a movable ejector and adjusting devices for said ejector, the said devices comprising the longitudinally movable rod E, a locking lever to engage therewith, and means to actuate said lever.

9. In a typographical machine, the combination of a movable ejector and adjusting devices for said ejector, the said devices comprising the longitudinally movable rod E formed with the notch E¹⁰, the locking lever provided with the pin H¹⁰ to engage in said notch, and a cam to act on said lever.

10. In a typographical machine, the combination of a movable ejector and adjusting devices for said ejector, the said devices comprising the longitudinally movable rod E, the spring G, an abutment lever for said spring, and a cam to act on said lever.

11. In a typographical machine, the combination of a movable ejector, actuating means therefor, and adjusting devices for said ejector, the said devices comprising the longitudinally movable rod E, the spring G, an abutment lever for said spring, and a cam to act on said lever, the said cam being operated simultaneously with the said actuating means.

12. In a typographical machine, the combination of a movable ejector, actuating mechanism therefor, a spring distinct from the actuating mechanism to maintain the ejector yieldingly in its normal position when the machine is at rest, and manually operable connections for moving the ejector in opposition to the spring; whereby said spring serves not only to maintain the ejector in its said position, but also to return it thereto when moved therefrom by the operation of said connections.

13. In a typographical machine, the combination of a movable ejector, devices operable at will for moving the ejector from its operative position, and means for preventing the movement of the ejector by said devices except when the parts are in their normal position of rest.

14. In a typographical machine, the combination of a movable ejector, devices operable at will for moving the ejector, and means for preventing the operation of said devices except when the parts are in their normal position of rest.

15. In a typographical machine, the combination of a movable ejector, manually operable devices for moving the ejector from

its normal position when the machine is at rest, and means for automatically returning it thereto at such time, together with mechanism for preventing the action of said means during the operation of the machine.

16. In a typographical machine, the combination of ejector mechanism, devices for adjusting said mechanism to provide blades of different widths, locking means to prevent the adjustment of said devices during

the operation of the machine, and automatic means to release said locking means when the machine comes to rest.

In testimony whereof I have affixed my signature in presence of two witnesses.

GEORGE P. KINGSBURY.
